UNITED STATES PATENT OFFICE.

EDWARD CAIRNS, OF JERSEY CITY, NEW JERSEY.

DESIGN FOR FIREMEN'S HATS.

Specification forming part of Design No. **11,176**, dated May 6, 1879; application filed April 10, 1879.
[Term of patent 7 years.]

To all whom it may concern:

Be it known that I, EDWARD CAIRNS, of Jersey City, in the county of Hudson and State of New Jersey, have invented a new and original Design for Firemen's Hats, of which the following is a description, reference being had to the accompanying drawing, making part of this specification.

A represents the brim, and B B' the combs, of the hat. Said combs may be surmounted by any desired ornament. The body C of the hat, between the several combs, is ornamented by a design which consists of a series of curved beads, b b', arranged to extend from the brim to the combs in transverse directions, and so that both sets of beads b b' intersect one another, leaving a series of lozenge and

arched shaped spaces, c c', between them, and giving to the sides and crown of the hat, between the combs, a lattice-work-like ornamental appearance.

I claim—

The design for a fireman's hat, consisting of a series of curved beads, b b', arranged to extend in transverse directions from the brim A to the combs B B', and intersecting one another to form a lattice-work-like ornament to the sides and crown of the hat between the combs, substantially as described, and as shown in the accompanying drawing.

EDWARD CAIRNS.
